PROCESS FOR PURIFYING POLYHALOGENATED CARBOXYLIC ACIDS

Edgar Fischer, Frankfurt am Main, Germany, assignor to Farbwerke Hoechst Aktiengesellschaft vormals Meister Lucius & Bruning, Frankfurt am Main, Germany, a corporation of Germany

Application November 6, 1957, Serial No. 694,870

6 Claims. (Cl. 260—408)

This invention provides a process for purifying crude polyhalogenated carboxylic acids and more especially polyhalogenated carboxylic acids containing fluorine and chlorine.

As starting material for the manufacture of polyhalogenated carboxylic acids there may be used polyhalogenated paraffin mixtures which may be obtained, for example, by the telomerization of polyhalogenated olefins carried out, for example, according to U.S. Patent 2,770,659 or by the cracking of high molecular weight perhalogenated polymers or copolymers of halogenated olefins according to the process described in U.S. patent application Serial No. 525,783, filed on August 1, 1955, by Edgar Fischer and Hans Helmut Frey for "Production of Fluorochlorocarboxylic Oils and Waxes" or according to other suitable processes. By a treatment with oxidizing agents the unsaturated constituents contained in the mixtures of saturated and unsaturated halogenated paraffins are converted into the polyhalogenated carboxylic acids. The saponification of the saturated constituents resulting in their transformation into polyhalogenated carboxylic acids can only be effected by means of an acid under very energetic conditions, for example, under the conditions described in U.S. patent application Serial No. 690,205, filed on October 15, 1957, by Edgar Fischer for "Process for the Manufacture of Polyhalogenated Carboxylic Acids."

The oxidation can be carried out in an acid medium as well as in an alkaline medium. An acid oxidation can, for example, be achieved by means of nitric acid while an alkaline oxidation can advantageously be effected by means of an alkali permanganate. These processes have inter alia been described in detail in U.S. patent application Serial No. 452,707, filed on August 27, 1954, by Gerhard Bier, Hans Helmut Frey and Karl Heinz Kahrs for "Method for the Preparation of Fluorinated Carboxylic Acids." In both cases it is, however, always mixtures of acids and unreacted unsaturated or saturated starting materials that are obtained. As is known, the separation of these mixtures and the purification of the crude polyhalogenated carboxylic acids involve great difficulties which are due, on the one hand, to the excellent emulsifying properties of these carboxylic acids which properties become apparent above all in an alkaline medium but also in an acid medium and, on the other hand, to the abnormal solubilities occurring in this class of substances.

Many metallic and non-metallic salts of these acids possess a pronounced good solubility in organic media. When the acids are separated from neutral substances by means of the alkali metal salts, a customary process in organic chemistry, obstinate emulsions form which can be broken by the addition of neutral salt solutions and, if necessary, by subjecting them, in addition thereto, to a centrifugation. By the addition of concentrated hydrochloric acid or the introduction of gaseous hydrogen chloride into the aqueous salt solution the crude poly-

2

halogenated carboxylic acids can be precipitated and separated as liquid heavy phase.

The impurities which are still contained in the crude acids at this point of the process are mainly alkali metal salts and water. The working up by vacuum distillation involves considerable difficulties. One reason for these difficulties lies in the presence of alkali metal salts which even in themselves strongly impede a vacuum distillation and which at an elevated temperature cause a decomposition of the acids into olefins, CO₂ and alkali halide. Nor can a vacuum distillation be carried out when the crude acids have carbon chains of more than 10 to 12 carbon atoms. To work up these products by distillation and to purify them it has hitherto been necessary to make use of the chlorides or of the esters of these acids with low molecular alcohols which have a much lower boiling point and which can be distilled more easily. These acid derivatives can moreover be subjected to higher temperatures in vacuo without any decomposition taking place.

Now I have found that the free acids, preferably those having carbon chains of 4 to 14 carbon atoms, which mainly contain fluorine and which may besides contain a second halogen atom such as chlorine or bromine and preferably chlorine, can also be distilled with superheated steam at temperatures of generally more than 100° C. without decomposition taking place if the distillation is carried out in the presence of at least one hydrogen halide such as hydrogen chloride or hydrogen bromide, preferably hydrogen chloride. The process of this invention does not require the application of a vacuum but can be carried out under normal pressure in a simple apparatus. Even when applying steam of more than 200° C. no phenomena of decomposition can be observed. In this process the addition of hydrogen halides and preferably hydrogen chloride has a double function. Firstly, it serves to prevent the formation of an emulsion ordinarily taking place in the condensate owing to the interaction of acids and water and secondly it considerably reduces the solubility in water, particularly that of the low molecular perhalogenated acids.

The hydrogen halide, preferably hydrogen chloride may be introduced into the distilling vessel, the cooling system or the collecting vessel in the form of an aqueous solution or in the gaseous state or simultaneously in the form of an aqueous solution and in the gaseous state. It is most advantageous to introduce it into a cooling system whereby the formation of an emulsion is successfully suppressed in the nascent state already.

The polyhalogenated carboxylic acids purified according to the present invention may be used, for example, as emulsifiers.

The following examples as well as the accompanying drawing serve to illustrate the invention without limiting it thereto, the parts being by weight.

Example 1

1000 parts of crude chlorofluorocarboxylic acids obtained by precipitating an alkali metal salt solution of chlorofluorocarboxylic acids with concentrated hydrochloric acid and by separating the lower liquid phase, the said fluorinated carboxylic acids having been prepared according to Example 1 of U.S. patent application Serial No. 690,205, filed on October 15, 1957, by Edgar Fischer for "Process for the Manufacture of Polyhalogenated Carboxylic Acids" and consisting of 94% by weight of chlorofluorocarboxylic acids having an average equivalent weight of 576, are added dropwise from stock vessel V into distiller B heated to 160 to 180° C. At the same time steam of 180° C. coming from superheater U is introduced into distiller B. The introduction of the crude acid is regulated so that there are only about 100

parts of product in distiller B at a time. The acid passing over together with the steam is condensed in condenser K. At 2 gaseous hydrogen chloride is introduced into the cooling system in such a quantity that the aqueous hydrochloric acid which forms contains 5 to 10% of hydrogen chloride. In separating vessel D the distilled chlorofluorocarboxylic acid separates as heavier phase and leaves at 4. The aqueous hydrochloric acid flows off via tube 3. The distillation with superheated steam is continued as long as chlorofluorocarboxylic acid passes over. 932 parts of distilled chlorofluorocarboxylic acid having an average equivalent weight of 568 and containing a residue on ignition of less than 0.05% by weight are obtained. The accompanying salts which have not been distilled (18 parts) remain in distiller B.

Example 2

When introducing gaseous hydrogen bromide instead of gaseous hydrogen chloride into the cooling system and when otherwise proceeding as described in Example 1, the distilled chlorofluorocarboxylic acid has a faint yellow shade which is caused by small quantities of free halogen. The latter can easily be eliminated in known manner, for example by passing through an inert gas. The yield amounts to 918 parts.

I claim:

1. A process for purifying polyhalogenated aliphatic carboxylic acids with 4 to 14 carbon atoms selected from the group consisting of fluorine-containing acids and of acids containing fluorine and a minor amount relative to fluorine of at least one halogen selected from the group consisting of chlorine and bromine, which comprises distilling the crude acid with superheated steam at temperatures of generally more than 100° C., at least one hydrogen halide selected from the group consisting of hydrogen chloride and hydrogen bromide being introduced into the distilling apparatus in the gaseous state simultane-

ously with the steam, whereby decomposition of the fluorine-containing acid is avoided.

2. A process for purifying polyhalogenated aliphatic carboxylic acids with 4 to 14 carbon atoms selected from the group consisting of fluorine-containing acids and of acids containing fluorine and a minor amount relative to fluorine of at least one halogen selected from the group consisting of chlorine and bromine, which comprises distilling the crude acid with superheated steam at a temperature of generally more than 100° C., at least one hydrogen halide selected from the group consisting of hydrogen chloride and hydrogen bromide being introduced into the distilling apparatus in the form of an aqueous solution simultaneously with the steam, whereby decomposition of the fluorine-containing acid is avoided.

3. A process for purifying polyhalogenated aliphatic carboxylic acids with 4 to 14 carbon atoms selected from the group consisting of fluorine-containing acids and of acids containing fluorine and a minor amount relative to fluorine of at least one halogen selected from the group consisting of chlorine and bromine, which comprises distilling the crude acid with superheated steam at a temperature of generally more than 100° C., at least one hydrogen halide selected from the group consisting of hydrogen chloride and hydrogen bromide being introduced into the distilling apparatus in the form of an aqueous solution and in the gaseous state simultaneously with the steam, whereby decomposition of the fluorine-containing acid is avoided.

4. A process as claimed in claim 1, wherein hydrogen chloride is introduced.

5. A process as claimed in claim 1, wherein a carboxylic acid containing chemically bound fluorine and chlorine is purified.

6. Acids whenever purified by the process as claimed in claim 1.
